FIG. 1.

Patented Nov. 21, 1922.

1,436,625

UNITED STATES PATENT OFFICE.

MESROB S. MAMOULIAN, OF NEW YORK, N. Y.

AMUSEMENT DEVICE.

Application filed August 31, 1921. Serial No. 497,176.

To all whom it may concern:

Be it known that I, MESROB S. MAMOULIAN, a citizen of the United States, and a resident of the city of New York, borough 5 of the Bronx, county of Bronx, and State of New York, have invented a new and Improved Amusement Device, of which the following is a description.

The general object of my invention is to 10 provide a novel device that will afford amusement especially to a group of young people and which will be a source of merriment by displaying an infinite variety of combinations, items of information, topical 15 contributions, a simulation of fortune telling, or the like, in a diverting manner.

The nature of the invention and its distinctive features and advantages will clearly appear as the description proceeds.

20 Reference is had to the accompanying drawings it being understood that the drawings are merely illustrative of one example of the invention.

Figure 1 is a face view of an amusement 25 device embodying my invention, a portion of the front being broken away;

Figure 2 is a section on the line 2—2, Figure 1.

In carrying out my invention in accordance with the illustrated example, a preferably oblong structure is provided, comprising a back 10 and a front 11, the front or back at the top and bottom being turned over to close the structure at the longitudinal side edges as indicated at 12. The front 35 11 is maintained spaced above the back by means of transverse partition strips 13 forming with each other slideways and the outermost strips 13 forming additional slideways 40 with end strips 13^a, a series of slideways being thus provided and running transversely of the structure.

In each slideway is a card 14, the side edges having guided engagement with the strips 13, 13^a, and each slide has secured thereto the shank 15 of an operating button or like device 16. Said shanks extend through the vertical slots 17 in the front 11, there being a slot 17 for the operating device 50 vice of each card.

Each card is divided into transverse parallel zones 18, each zone bearing a number or other identifying symbol, the series of identifying symbols running in order, as for 55 example, 1 to 10. A row of indicating symbols 19 is produced on the front 11 along

each slot 17, corresponding with the symbols of the zones 18 but in the reverse order.

In the front 11 is produced at each card a longitudinal sight opening 20 adjacent to 60 the longitudinal medial line of the structure, the openings being of a width to display each a single zone of a card 14.

The zones 18 have each reading matter thereon or other matter to be displayed and 65 the device is utilized by each of the players selecting a number arbitrarily made up of combinations of the numbers on the front 11, whereupon the respective operating devices 16 are moved to the index symbols 19 70 to represent the selected number, thereby displaying at the sight openings 20 a succession of zones 18 with the various reading matter thereon.

I would state in conclusion that while the 75 illustrated example constitutes a practical embodiment of my invention, I do not limit myself strictly to the exact details herein illustrated, since, manifestly, the same can be considerably varied without departure 80 from the spirit of the invention as defined in the appended claims.

Having thus described my invention, I claim:

1. As a new article of manufacture an 85 amusement device including a structure having a back and front, transverse partitions spacing the back and front from each other and forming parallel slideways between the back and front, said front having a longitudinal opening at each slideway and having parallel vertical slots, cards slideable in said slideways to a position concealed by the front or to dispose given zones of the respective card at the said openings, and card-operating devices movable in said slots and fixed to said cards, said cards divided into transverse zones presenting each different reading matter, the zones having identifying symbols and there being vertical rows of 90 corresponding symbols on the front of the structure in the reverse order of the symbols on the cards. 95

2. As a new article of manufacture an 100 amusement device of the character described 105 having a front formed with a longitudinal series of sight openings and with vertical slots, and a series of cards slideable beneath said front and each divided into transverse zones bearing identifying symbols in series, 110 said zones presenting each its distinctive reading matter and operating devices on

said cards and extending through said slots for the optional movement of the cards, said front having at the slots thereof indicating symbols corresponding with those of the 5 cards but in reverse order for positioning the operating means to selectively display combinations of the respective card zones at said openings.

3. As a new article of manufacture an 10 amusement device having sight openings, and a plurality of slideways at said openings, a plurality of slides disposed in the slideways in a plane at the back of said openings and each slide bearing matter that

may be displayed at the sight openings, a 15 portion at a time, operating means on the slides to move the same past the sight openings, there being distinguishing indicating marks on the device at the front thereof at each slideway, and spaced to correspond 20 with portions of the display matter so that a series of indicating marks may be selected one at each slideway and the operating means moved to given indicating marks thereby exhibiting certain of the display 25 matter of each slide at the sight openings.

MESROB S. MAMOULIAN.
